UNITED STATES PATENT OFFICE.

DANIEL E. RILEY, OF SEATTLE, WASHINGTON.

BODY-RUBBING DEVICE.

1,345,026.

Specification of Letters Patent. Patented June 29, 1920.

Application filed December 14, 1918. Serial No. 266,687.

To all whom it may concern:

Be it known that I, DANIEL E. RILEY, a citizen of the United States, and resident of the city of Seattle, county of King, and State 5 of Washington, have invented certain new and useful Improvements in Body-Rubbing Devices, of which the following is a specification.

My invention relates to bath appliances 10 and consists of a body rubbing device. The object of my invention is to provide a body rubbing device in the nature of a towel, or a strip of fabric, which is provided with means whereby it may be more effectively 15 used, and particularly so constructed that it may better enter the hollows of the back, so as to be able to rub it effectively.

Another advantage of my invention is that the fabric is, by reason of the insertion of 20 the sponge, prevented from forming a rope-like mass and maintains a flat and ample rubbing surface.

My invention consists of the novel parts 25 and combinations of parts which will be hereinafter particularly defined by the claims. The preferred form of construction is shown in the accompanying drawings.

Figure 1 is an edge view of the device, with a portion broken away at one pocket to 30 better show the distending mass placed therein.

Fig. 2 is a face view of the same device also with a portion broken away at one pocket.

Fig. 3 is a side view of a slightly modified construction.

Fig. 4 is an edge view of the construction shown in Fig. 3, in which only one pocket has been provided with the sponge member.

40 In using a bath towel for rubbing the body, and more particularly for rubbing the back, it is not possible to rub the body effectively in the hollow along the center of the back. It is one purpose of my invention to 45 provide means whereby this portion of the back may be effectively rubbed and, in addition to this, to provide means whereby the water carrying capacity of a sponge may be employed so as to provide water during the 50 rubbing action.

In constructing this device I take a strip of fabric, which might well be a portion of an ordinary bath towel, or of fabric resembling a bath towel in its construction. I 55 fold this strip of fabric 1, upon itself along

a longitudinal line, so as to form two thicknesses extending lengthwise thereof. The edges of the fabric are then stitched together so as to form a tube. This tubular fabric may be left open at the ends, as shown in 60 Figs. 1 and 2, so that, if desired, the hand may be inserted therein and thus form what is in the nature of a mitten, which may be used to better rub the body.

If desired, however, the ends of the fabric 65 strip may be folded over and stitched down, as shown at 10, to thereby form an enlarged or thickened band which enables it to be more securely and firmly gripped by the hand. The mitten effect may be secured 70 even with this construction, by omitting to stitch for a short distance along the edge, as at 11, thus leaving an opening into which the hand may be inserted.

Toward the center of the tube thus formed, 75 the fabric is stitched across, as shown at 2. In this way a series of pockets are formed. These pockets may vary in number from one to any number desired. These pockets have an opening, preferably at one edge, as at 3, 80 whereby a distending body may be inserted therein. When so inserted there is no tendency of the body to drop out, as, while the device is in use, it is under strain lengthwise, which tends to close this opening and to 85 cause the sides of the tube to draw upon the body. It is evident that this opening may be otherwise located.

While the character of this distending body may be widely varied, I prefer, for 90 most purposes, to employ a porous, flexible body, which will act as does a sponge, to hold and give out water. Such a body being flexible and capable of being compressed, will bend and fit the curves of the body and 95 at the same time will give out water which is effective for scrubbing purposes.

This distending body may be a sponge, a piece of spongy rubber, or any other analogous material, and in some cases might be of 100 a material differing widely from such products. The exact character of the material used is immaterial. If desired, a cake of soap might be temporarily inserted in one of the pockets.

105 In use, this device is employed just as would be a towel, the ends being grasped by the hands and the center portion passed over some portion of the body and the whole drawn back and forth. In using this device 110

for rubbing the back, the enlarged portions formed by the inserted sponge-like masses 4, for a bulge or projection which fits into the hollow of the back. They also serve as 5 a carrier for water. It is, therefore, possible to more effectively rub and scrub the back than with an ordinary towel. The water holding capacity of the sponge is enough to greatly assist the scrubbing action.

10 What I claim as my invention is:

1. A body rubbing device comprising a fabric strip folded and stitched to form pockets near the middle of its length for the reception of a compressible filler, and 15 pockets stitched in the fabric at the ends of

said strip for the insertion of the user's hands.

2. A body rubbing device comprising a fabric strip folded longitudinally upon itself to bring its side edges together, the same 20 being stitched along its edge and stitched across at spaced intervals near the middle of its length to thereby form pockets for the reception of a compressible filler, a portion of the stitching along the edge near the ends 25 of the strip being omitted to form pockets for the insertion of the user's hands.

Signed at Seattle, Washington, this 7th day of December, 1918.

DANIEL E. RILEY.
